UNITED STATES PATENT OFFICE.

FRANK L. PURCELL, OF FREDERICK, OKLAHOMA.

BARREL-SUPPORT.

1,250,655.

Specification of Letters Patent.

Patented Dec. 18, 1917.

Application filed December 21, 1916. Serial No. 138,250.

To all whom it may concern:

Be it known that I, FRANK L. PURCELL, a citizen of the United States, residing at Frederick, in the county of Tillman and State of Oklahoma, have invented certain new and useful Improvements in Barrel-Supports; and I do declare the following to be a full, clear, and exact description of the invention, such as will enable others skilled in the art to which it appertains to make and use the same.

This invention relates to new and useful improvements in barrel supports, and the primary object of the invention is to provide a support for barrels that holds them in such a manner that they may be conveniently and easily tilted to and from the horizontal to enable the contents of the barrel to be completely drained therefrom.

Another object of the invention is to provide a barrel support of this character with a movable receptacle supporting platform that is disposed adjacent thereto and connects with the tilting mechanism of the support so that the receptacle supported by the platform will be maintained in operative relation when the barrel is tilted.

A further object of the invention is to provide a device of this character which is simple and durable in construction, inexpensive to manufacture, and one which will be very efficient in operation.

With these and numerous other objects in view, the invention consists of the novel features of construction, combination and arrangement of parts which will be herein-after referred to and more particularly pointed out in the specification and claims.

In the accompanying drawings:

Fig. 1 is a side elevation of the barrel support in one position;

Fig. 2 is a longitudinal vertical section of the support in another position;

Fig. 3 is a top plan view;

Fig. 4 is an end elevation;

Fig. 5 is a transverse vertical section taken on the line 5—5 of Fig. 1;

Fig. 6 is a detail vertical section taken on the line 6—6 of Fig. 2;

Fig. 7 is an enlarged detail end view of the rack bar supporting brackets; and,

Fig. 8 is a front elevation of the barrel holder, showing the barrel locking means at the front end of the same.

In describing this invention I shall refer

to the drawings in which similar reference characters designate corresponding parts throughout the several views. The barrel support comprises a substantially rectangular base frame 1 which is provided with a cross bar 2, and which has projecting upwardly from the frame at each of its opposite sides a pair of inclined bars 3 which form upright supports. These inclined bars 3 have their upper ends contacting and form the apices of triangles formed by the same and the sides of the base frame. A supplemental frame is provided adjacent the top of the inclined bars 3 which is disposed parallel with the base frame 1. This supplemental frame which is designated by the numeral 4 is formed of two parallel side bars having their opposite ends secured to the inclined bars 3, and which are connected by diagonal cross strips 5. The supplemental frame or additional frame is also provided with a cross strip 6 and to additionally strengthen this frame structure, I have provided a substantially U-shaped supporting member 7 that has its opposite ends secured at the contacting terminals of the inclined bars 3 and which has its bottom portion secured to the junction of the strips 5 and 6 by a rivet as clearly shown at 8 in the drawings.

The barrel or cask is held in position in a substantially rectangular barrel supporting frame 9 which is mounted on a horizontal axis 10 at the contacting upper ends of the inclined bars 3 between the uprights 90 formed thereby. This rectangular shaped supporting frame is provided with angular end bars 11 which are curved as shown at 12, and have their end portions extending upwardly to form stops for a barrel or cask that may be disposed in the frame. The frame is also provided with curved cross strips 13 and the horizontal axis 10 is likewise curved to correspond to the cross strips and the ends. To additionally support the barrel in the frame without any chance of it slipping therefrom, one end of the frame which shall be called the rear end, is provided with an additional strip 14 extending thereacross and projecting above 105 the end bar. The end bars 11 are provided with projecting end portions 15 which are adapted to limit the swinging movement of the barrel supporting frame as after either end of the frame is swung downwardly be- 110

yond a certain point, these projecting ends will contact with the inclined bars 3 and thus stop the frame.

Secured to the rear end of the frame 9 is 5 a U-shaped bracket 16 which has pivotally mounted between its sides the upper end of a T-shaped rack bar 17. This T-shaped rack bar has teeth formed in the lower end of the shank portion and when in position 10 depends from the frame for a purpose to be hereinafter more fully described. The upper end of the rack bar 17 is pivotally connected to the frame and it is adapted to swing on the pivot when said frame is tilted.

15 Extending transversely beneath the additional supporting frame 4 and mounted in bearings 18 depending therefrom, is a rotatable shaft 19 that extends transversely across this frame and has at one end of the 20 same a crank 20. This crank 20 is disposed outside of the adjacent upright, so that it is within easy reach of the operator. Mounted on the shaft 19 intermediate its ends is a pinion 21 that is adapted to operatively engage the rack bar 17. The rack bar is held into engagement with the pinion by means of a substantially U-shaped frame 22 mounted on the shaft surrounding the pinion and said frame having its free ends connected by 25 a rod 23 upon which is mounted a roller 24. When the rack bar is disposed in engagement with the pinion, the flat upper portion of the same will engage the roller 24 on the frame 22, and, owing to the fact that this 30 roller is disposed adjacent the pinion, the rack bar will be prevented from becoming disengaged therefrom.

From the foregoing description, it will be 35 obvious that when it is desired to tilt the frame 9, it is only necessary to rotate the shaft 19 by means of the crank whereupon, owing to the fact that the pinion 21 is in operative engagement with the rack bar, the frame may be easily moved. To lock the 40 barrel supporting frame at various tilted positions I provide a chain 25 which depends therefrom adjacent one end and which is adapted to have one of its links engage a stud 26 that depends from the adjacent upright bar 3. By this means, when the barrel supporting frame is tilted forward, as 45 there will be a constant downward pressure on the same, by hooking one of the links of the chain over the locking stud 26, the other 50 end of the tilting frame will be prevented from moving and the frame consequently 55 will be locked.

At the front end of the base frame 1, I 60 provide a receptacle supporting platform which when in position, is disposed beneath the front end of the barrel supporting frame and adjacent the same, so as to be held in operative relation therewith to receive the contents of the barrel when it is opened. 65 This receptacle supporting platform, which

is designated by the numeral 27, is held in operative position by U-shaped arms 28 which have laterally bent ends pivotally mounted in the opposite sides of the base frame 1. Upon using these arms, the platform is adapted to swing so that it will always be disposed in operative relation with the front end of the barrel supporting frame. To move this receptacle holding platform I connect the same with the lower end of the 70 rack bar 17 by means of a chain 29. This chain 29 is connected by a link 30 with the lower end of the rack bar, while the opposite end of the same is adapted to engage a hook 31 on the rear edge of the platform. The 75 end of the chain that engages the hook 31 is detachably connected therewith so that the chain may be adjusted to various lengths by moving different links of the same into locked engagement with the hook.

To additionally hold a barrel or cask in the barrel supporting frame, I provide at the front end of the same a locking member 32 which is composed of a strip secured to the outer surface of the front end of the 80 frame, and pivotally and slidably connected therewith as shown at 33. The upper end of this locking member 32 is hook-shaped as shown at 34, and when in operative position, the hook is adapted to engage a faucet or 85 the like that may be placed in the front end of the barrel or cask. By this means the barrel or cask will be additionally locked in 90 position and will be prevented from being accidentally displaced from the supporting 95 frame when in operation.

In operation, when it is desired to use this 100 barrel support, the supporting frame is tilted by operation of the rack and pinion to the limit of its movement at either side of one of the uprights. When in this position, a barrel or cask may be easily placed on the frame, and owing to the construction of the same, the barrel will be securely held in position. When a faucet is placed in the front end, the 110 locking member 32 engages the same to securely lock the frame to the barrel or cask. The supporting frame is then swung back to horizontal position when the device is ready 115 for use to draw the contents from the barrel.

When the parts of the device are positioned as shown in Fig. 1 of the drawings, and it is desired to remove some of the contents of the barrel, a receptacle is placed upon the supporting platform 27 and the 120 rack and pinion operated to swing the front end of the barrel supporting frame downwardly in a receding arc. Owing to the fact that the rack bar to operate the tilting frame moves upwardly, and as the 125 lower end of this rack bar is connected with the swinging receptacle supporting platform, this platform will be swung inwardly, so that it will always be held in predetermined operative relation with the 130

front end of the frame. This receptacle supporting platform is so disposed that it will be in operative relation with the outlet of the barrel when the barrel is horizontal, and as the contents of the barrel are used and it is required that the same be tilted forward, owing to the connection between the tilting means of the barrel supporting frame, this platform will be drawn inwardly so as to always hold the receptacle thereon in the same relation. As the supporting frame is again lifted, the platform will swing back to its normal position. The relation of parts when the front end of the frame is tilted, and the receptacle supporting platform is moved inwardly, is shown clearly in Fig. 2 of the drawings.

This device will be found especially useful in retailing oil, molasses, etc. that are shipped in large barrels and casks and by the use of this holder the contents thereof may be very easily drawn therefrom. The barrel will always be easily accessible and the contents will readily run therefrom as the barrel may be tilted to such an angle that all of the contents will readily drain from its interior. The barrel supporting frame, base and additional frame, and uprights are preferably formed of angle iron, although if desired, any suitable construction may be employed.

From the foregoing description of the construction and operation of my new and improved barrel support, the manner of applying the same to use and the operation thereof will be readily understood, and it will be seen that I have provided a simple and efficient means for carrying out the objects of the invention.

40 I claim:—

1. A device of the class described, comprising a tilting barrel support, a receptacle holding support, and means for simultaneously moving the receptacle support when the barrel support is tilted to maintain the same in operative relation.

2. A device of the class described, comprising a tilting barrel support adapted to have one end swung downwardly in a receding arc, a receptacle holding support disposed below the barrel support adjacent said end, and means to simultaneously move the receptacle support when the bar-

rel support is tilted in predetermined relation with the arc of its adjacent end. 55

3. A device of the class described, comprising a tilting barrel support, a receptacle holding platform disposed below the barrel support adjacent one end, swinging arms supporting said platform; and connecting means between said platform and the barrel support to maintain the platform in continued operative relation when the barrel support is tilted. 60

4. A device of the class described, comprising a barrel support mounted on a horizontal axis, means to tilt said support, a receptacle supporting platform disposed beneath the barrel support adjacent one end, swinging arms supporting said platform, 70 and connecting means between the platform and the barrel support tilting means, whereby the platform is maintained in operative relation when the barrel support is tilted. 65

5. A device of the class described, comprising a pair of upright supports, a barrel supporting frame mounted on a horizontal axis between said uprights, a rack bar depending from one end of the barrel supporting frame, a pinion to operate said 80 rack to tilt the barrel supporting frame, a swinging receptacle holding platform disposed beneath the barrel supporting frame adjacent its opposite end, and an adjustable connection between the platform and the rack bar whereby the platform is moved when the rack bar is operated. 75

6. A device of the class described comprising a substantially rectangular shaped tilting barrel supporting frame mounted on 90 a horizontal axis extending transversely across the same, curved transverse cross bars and end bars between the sides of the frame, upwardly projecting portions on said end bars, and a locking member slidably and pivotally mounted on the front end bar adapted to engage the faucet of a barrel in the supporting frame. 95

In testimony whereof I have hereunto set my hand in the presence of two subscribing 100 witnesses.

FRANK L. PURCELL.
